(57) CLAIM

The ornamental design for a light-emitting diode, as shown and described.

DESCRIPTION

FIG. 1 is a perspective view as viewed from a portion above a light-emitting diode embodying my new design;

FIG. 2 is a perspective view as viewed from the rear of the light-emitting diode;

FIG. 3 is a perspective view as viewed from a portion below the light-emitted diode

FIG. 4 is a front view thereof;

FIG. 5 is a rear view thereof;

FIG. 6 is a top plan view thereof;

FIG. 7 is a bottom view thereof;

FIG. 8 is a right side view thereof; and,

FIG. 9 is a left side view thereof.
